CLAIM

The ornamental design for a wall bracket for a hand-held blower, as shown and described.

DESCRIPTION

FIG. 1 is a perspective view of a wall bracket for a hand-held blower showing our new design;

FIG. 2 is an environmental perspective view with the broken line showing of a blower being for illustrative purposes and forms no part of the claimed design;

FIG. 3 is a front elevational view;

FIG. 4 is a left side elevational view;

FIG. 5 is a right side elevational view;

FIG. 6 is a top plan view; and,

FIG. 7 is a bottom plan view.
